COOLING APPARATUS

Filed April 25, 1925

UNITED STATES PATENT OFFICE

GEORGE E. COX, OF NIAGARA FALLS, NEW YORK, ASSIGNOR TO AMERICAN CYANAMID COMPANY, OF NEW YORK, N. Y., A CORPORATION OF MAINE

COOLING APPARATUS

Application filed April 25, 1925. Serial No. 25,764.

This invention relates to cooling apparatus, more particularly to means for cooling hot materials, such as burnt lime discharged from the kiln.

It is common practice to burn lime in inclined rotary kilns by continuously introducing in the upper end thereof, limestone which has been crushed to the desired size, say egg. The limestone in moving towards the lower end of the kiln is subjected to the temperature of hot gases of combustion of powdered coal, oil or gas, and is thus converted into burnt lime, which leaves the kiln at a red heat. Before using, storing or shipping the same it is necessary to cool the hot burnt lime and this was generally accomplished by tumbling it in a rotating, inclined metal drum which was cooled by an air blast.

For certain purposes, such as in the production of calcium carbide by the interaction of lime and coke, it is highly desirable that the lime be in the form of lumps and that the amount of fines be reduced to a minimum. The reason for this is that in the electric furnace used for making the carbide the fines are, to a large extent, blown out and lost, instead of reacting to form the carbide. In the old method of cooling the hot burnt lime by tumbling, a large amount of fines was formed, constituting a serious loss of material.

My invention is intended to obviate this difficulty, it being among the objects thereof to provide a method of cooling burnt lime and other materials so as to prevent the formation of an excessive amount of fines.

It is a further object of my invention to provide an apparatus for cooling the burnt lime which shall operate substantially continuously.

In practicing my invention, I provide a metal surface over which the hot, burnt lime is caused to pass in such a manner as to minimize the tendency thereof to produce fines. This is accomplished by pushing the lime over the surface by means of conveyor members secured to an endless chain, and avoiding excessive rolling or tumbling of the pieces of lime as in the old drum type of cooler. The surface of the metal plate is

kept cool by the circulation of water through a plurality of compartments formed under the plate and the amount of cooling is capable of close regulation to give uniform conditions. For convenience I utilize an I-beam which is placed in a horizontal position, and I form the water compartments in the portion below the web by welding suitable pieces thereto. The conveyor members fixed on an endless chain are adapted to function in the through portion above the web. Guiding means are provided to prevent lime from falling over the sides of the conveyor structure, which rests on rollers which allow for expansion and contraction due to temperature changes and avoid any strains on the structure.

In the accompanying drawing constituting a part hereof, and in which like reference characters indicate like parts:

Fig. 1 is a fragmentary plan view of my cooling apparatus for hot lime.

Fig. 2 is a fragmentary side elevational view thereof:

Fig. 3 is a vertical, cross-sectional view taken along the line III—III of Fig. 2, and

Fig. 4 is a vertical, cross-sectional view taken along the line IV—IV of Fig. 2.

I provide an I-beam 1, which is placed in a horizontal position and has metal plates 2 and 3 welded or otherwise secured along the sides thereof, enclosing a trough shaped space in which the conveyor members function to move the hot lime or other material to be cooled over the surface of the web of the I-beam. Across the lower side of the beam is secured a plate 4 preferably by welding, the said plate forming with the web and the lower portion of the sides of the I-beam, a chamber for the circulation of water. The chamber is divided into a number of compartments by baffle plates 5 which are welded in place. The structure is movably supported by the provision of bearing plates 6 at predetermined intervals along both sides of the I-beam, which plates bear upon grooved portions 7 of rollers 8, which in turn rest upon the vertically disposed flanges of angle bars 9, in alignment with plates 6, and permanently secured in concrete foundations 10.

An inlet or feed pipe 11 has branches of flexible armored hose 12, controlled by valves 13 and terminating in twin inlet pipes 14 leading into one of the ends of each of the compartments. At the other end of each of said compartments is an exit pipe 15 formed with a goose-neck 16 having a free discharge opening 17 at a point above the top of the conveyor and discharging into the pipe 18 connected to the main outlet pipe 19. A valve 20 is interposed between pipe 15 and pipe 18 in order to by-pass the free discharge opening 17, if so desired. Conveyor members 21, of any desired type, operating in the space above the web of the I-beam are connected to an endless chain, not shown, as is common in conveyors of this general type.

In practice, the conveyor members 21 are set in motion by the actuation of a chain, and hot burnt lime or other material from a rotary kiln or other source is continuously fed into the path of the conveyor members, which push the same over the surface of the web of the I-beam, which is cooled by the circulation of water in the compartments below. By reason of the relatively small compartments, the temperature of the web is kept fairly constant and but slightly above the temperature of the incoming water, and the provision of a free discharge opening 17 assures a constant circulation of water at a predetermined rate and prevents the stagnation or obstruction of the flow of water therethrough, thus giving uniform conditions in the cooler at all times. Mounting the structure on rollers prevents any undue strain from being imposed upon the apparatus by permitting the apparatus to move freely upon changes in dimensions due to expansion or contraction and allows the conveyor-cooler to be made of a relatively great length.

It will be noted that the conveyor trough is of extremely simple construction, consisting essentially of standard shapes which may be readily obtained on the open market and secured together by welding or in other well-known manner. Ordinary piping and fittings are used in the construction, not only rendering the same inexpensive, but making replacements of worn or damaged parts a simple and inexpensive procedure. In my new cooling apparatus, because of the short compartments and the method of control of the flow of water, cooling is very effective, and since there is less tumbling action on the burnt lime, the amount of fines produced is small. Furthermore, this apparatus combines the functions of a conveyor for the material with a cooler.

Although I have described the operation of my apparatus for the cooling of burnt lime, it is apparent that other materials of a similar character or even having entirely different characteristics may be cooled there-

in. The details of construction, as well as the arrangement of the parts of the apparatus may be altered. For instance, instead of mounting the apparatus upon rollers, which are adapted to move and thus to compensate for the expansion and contraction of the apparatus upon changes in temperature thereof, I may firmly secure the same to a foundation or I may secure the same at some points and mount it upon rollers or similar structures at other points.

In Fig. 1 of the drawing I have shown the I-beam made up of a plurality of short I-beams cut diagonally and secured together. This construction is desirable for the reason that, with a diagonal joint I avoid any danger of the conveyor members catching on the adjoining edges if they are not in perfect alignment or one is slightly higher. However, this is not essential as the joint may be made transversely of the I-beam. If desired, I may place baffles only partially across the water chamber instead of dividing the same into independent water compartments; or I may place within the compartments a number of such baffles to aid in the positive circulation of water. These and other changes may be made in my invention, the scope of which is defined in the claim appended hereto.

What I claim is:

1. Cooling apparatus comprising a hollow stationary base, having up-standing sides forming a trough for receiving material to be cooled and along which said material may be conveyed, means for passing a cooling liquid through the hollow portion of said base, and means for maintaining a constant head of the cooling liquid above the hollow base.

2. Cooling apparatus comprising a substantially horizontal I-beam, and a plate welded to the lower side edges thereof to provide a chamber for cooling liquid, the upper sides of the I-beam forming a trough or channel for the material to be cooled and along which the material may be conveyed.

3. Cooling apparatus comprising a substantially horizontal I-beam, a plate welded to the lower side edges thereof to provide a chamber for cooling liquid, and baffles welded in said chamber forming a plurality of compartments, the upper sides of the I-beam forming a trough adapted to receive material to be cooled and along which said material may be conveyed.

4. Cooling apparatus comprising a substantially horizontal I-beam made of a plurality of sections joined together at their ends along a diagonal line, a plate fastened to the lower side edges of the I-beam to provide a chamber for cooling liquid, and baffles welded in said chamber forming a plurality of compartments, the upper sides of said I-beam forming a trough for receiving material to be

cooled and along which the material may be conveyed.

5. Cooling apparatus comprising a substantially horizontal I-beam, a plate welded to the lower side edges thereof to provide a chamber for cooling liquid, and plates attached to the sides of said I-beam and extending above the upper side edges thereof to form a trough for receiving material to be cooled and along which said material may be conveyed.

In testimony whereof, I have hereunto subscribed my name this 17th day of April, 1925.
